FILM TANK AGITATOR

William H. Carr, Jr., Washington, D. C.

Application September 30, 1947, Serial No. 776,921

2 Claims. (Cl. 259—75)

1

This invention relates to agitators for film tanks.

An object of the invention is the provision of an agitator for film tanks in which the agitation may be timed as desired, the holder for the tanks being so constructed that it may be adjusted to support tanks of varying sizes.

Another object of the invention is the provision of a mechanism for rocking tanks in which films are placed in a solution, the timing of the rocking being controlled by a thermostat in circuit with a relay that causes closing of a switch in a circuit of a magnet for rocking a holder for the tank against tension of a spring normally retaining the holder in a predetermined position.

Another object of the invention is the provision of a mechanism for rocking tanks containing a solution for treating photographic films or plates, the tanks being mounted in a pivoted and adjustable holder which is rocked periodically by an energized magnet acting on an armature attached to the holder, the timing of the rocking being controlled by a thermostat including an adjustable member for varying the time at which a circuit to the magnet is closed.

The invention consists in the novel construction, arrangement and combinations of parts hereinafter more particularly described and claimed.

In the drawings,

Figure 1 is a view in perspective of a mechanism for agitating tanks for films,

Figure 2 is a vertical longitudinal section of the mechanism and illustrating the manner of mounting a film tank,

Figure 3 is a fragmentary plan view of the holder for a tank, and

Figure 4 shows more or less diagrammatically, a wiring diagram for agitating the device.

Referring more particularly to the drawings 10 designates a base member formed of metal. Three tongues are stamped from the metal base being bent upwardly to form a pair of parallel standards 11 and 12 and a standard 13 adjacent one end of the base.

A holder 15 for a tank 16 (see Figure 2) which is adapted to contain a solution for treating photographic films or plates is pivotally mounted for rocking movement on the upper ends of the standards 11 and 12, as will be described. The holder includes a flat elongated steel plate 17 which has upturned side flanges 18 and 19. Tongues 15' are struck from each flange 18 and 19 and are bent downwardly below the plate 17. A pivot pin 15^a connects each tongue with the

adjacently disposed upper ends of one of the standards 11 and 12 for pivotally mounting the holder intermediate the ends of the plate 17. The flanges terminate at an inner tapered portion 20 of the plate. Each flange is provided with a pair of horizontally aligned slots 24 and 25. A movable slide 26 formed of wood or other suitable material has projections 27 at its opposite ends received by the slots 24 of the flanges 18 and 19. A similar slide 30 has projections 31 received by the slots 25 of the flanges. All of the projections are rectangular in cross section to prevent turning in the slots. The inner wall of each slide is faced with a rubber mat 32 which may be in the form of sponge rubber, the latter engaging the side walls of the film tank 16 as shown in Figure 2.

A bolt 35 is secured to each flange 18 and 19 and projects laterally therefrom. Each bolt is provided with an eye 36 at the free end thereof to receive the inner ends of springs 37 and 38. The outer ends of the springs 37 are attached to an eye bolt 39 mounted in each of the projections 27 on the slide 26, while an eye bolt 39^a extending from each of the projections 31 of the slide 30 is connected to the outer ends of the spring 38. By this construction, the pairs of springs 37 and 38 tend at all times to pull the slides 26 and 30 toward each other for clamping the film tank 16 between the rubber mats 32.

A coil spring 40 has one end secured at 41 to the outer end of the plate 20 while the other end of the spring is connected to a lug 42 struck up from the metal base 10.

A mechanism is provided for pulling downwardly upon the inner end of armature 20 periodically against the tension of the spring 40 and such mechanism includes an electromagnet 45 mounted on the base 10 and energized by an electrical current. Wires 46 and 47 are connected with a coil 48 of the electromagnet (see Figure 4).

A double pole double throw 110 volt A. C. commercial relay of the time delay type is represented by member 52. The relay includes an armature 51 upon which contacts 54 and 63 are mounted operable against fixed contacts 71 and 64 respectively by a spring 53. When the relay coil 50 is energized the relay armature 51 is attracted and the movable contacts 54 and 63 are pulled against fixed contacts 55 and 72 respectively. This action energizes the electromagnet 45 which in turn attracts the armature 20. The circuit energizing the electromagnet 45 comprises the following members: wires 57 and 58, contacts 54 and 55, wire 47, electromagnet winding 48 and

wires 46 and 58. An attachment plug 59 (Figure 1) forms the connection with the source of current. Fixed contacts 71 and 72 on the relay are not used electrically but are used as mechanical stops.

The time delay feature of the relay is provided by a heating coil 60 encircling a thermostatic strip 61 having a contact 70 mounted on the free end thereof. When the heating coil 60 has raised the temperature of the thermostatic strip 61, this member bends downwardly bringing the contact 70 against adjustable contact 68. This action energizes relay coil 50 causing the armature 51 to be attracted and pulling movable contacts 54 and 63 against fixed contacts 55 and 72 respectively. This action also separates movable contact 63 from fixed contact 64 which breaks the circuit energizing the heating coil.

The operation of my device is as follows: The film tank 16 is supplied with the proper solution and the films to be treated are disposed therein. At this time, the mechanism will be in the position shown in Figure 2. The member 59 is then plugged into a socket connected with a source of electrical current so that the current will pass through wires 57 and 73 through the heating coil 60, through wire 62, contacts 63 and 64 and wires 65 and 58. Since the spring 53 draws the armature 51 away from the relay coil 50 when no current is passing through said coil, the contacts 63 and 64 are in engagement and in position to maintain a closed circuit to the heating coil.

The thermostatic strip 61 with the contact 70 is bent downwardly when sufficiently heated by the heating coil to so as to cause the engagement of contact 70 with the adjustable contact 68. When this occurs the relay coil is energized and attracts the armature 51. The preceding circuit makes use of the following members in proper sequence: wires 57 and 73, thermostatic strip 61, contacts 70 and 68, relay coil winding 69 and wires 67 and 58. When the armature 51 is drawn against the contacts 72 and 55 two actions take place. First, the electromagnet 45 is energized by means of the following members: wire 57 and 56, contacts 54 and 55, wire 47, electromagnet winding 48 and wires 46 and 58. Second, the circuit through the heating coil 60 is broken since this circuit depends on contacts 63 and 64 being in engagement. When the electromagnet 45 is energized it draws the armature 20 downwardly against the tension of the spring 40 thus rocking the holder 15 in a direction which is opposed to the action of the spring. As the thermostatic strip 61 is no longer heated it cools and moves upwards causing contact 70 to become disengaged from contact 68. This action breaks the

circuit through the relay coil winding 69 which de-energizes the relay coil and allows the spring 53 to return the armature 51 to its original position. When the armature 51 returns to its original position contact 54 is separated from contact 55 thus breaking the circuit through the electromagnet winding 48 and allowing the spring 40 to return the armature 20 to its original position. When the armature 51 is in its original position contact 63 is in engagement with contact 64 thus energizing the heating coil 60 and causing the entire operation to take place again. The number of operations per minute is dependent on the setting of the adjustable screw 68.

I claim:

1. In a mechanism for rocking a film tank containing a solution for treating photographic films, a holder for the film tank comprising an elongated metal bottom plate having upstanding parallel side flanges extending for a portion of the length of the plate, said flanges having spaced and horizontally aligned elongated slots, a pair of spaced slides between the flanges, a projection on the end of each slide received by an adjacently disposed slot for guiding the slides towards or away from each other and springs connected between the projections tending to draw the slides toward each other, a resilient pad on the inner face of each slide adapted to engage a wall of the film tank, and means pivotally mounting the plate intermediate the ends thereof.

2. In a mechanism for rocking a film tank containing a solution for treating photographic films, a holder for the film tank comprising an elongated metal plate having upturned side flanges extending approximately from one end thereof and terminating inwardly of the opposite end of the plate, parallel slides between the flanges, means urging the slides toward each other for clamping a film tank therebetween, a base member below the plate, standards rising from the base member and means pivotally connecting an intermediate portion of the plate with the upper ends of the standards.
